Inventor:

John D. Pedersen,

By his atty, J. H. Richards

UNITED STATES PATENT OFFICE.

JOHN D. PEDERSEN, OF JACKSON, WYOMING.

FIREARM.

1,390,380.

Specification of Letters Patent. Patented Sept. 13, 1921.

Application filed December 16, 1919. Serial No. 345,176.

To all whom it may concern:

Be it known that I, JOHN D. PEDERSEN, a citizen of the United States, residing in Jackson, in the county of Lincoln and State 5 of Wyoming, have invented certain new and useful Improvements in Firearms, of which the following is a specification.

This invention relates more especially to that class of firearms usually designated as 10 small arms, and a principal object of the invention is to furnish an improved grip-safety device, particularly applicable to auto-loading and automatic pistols.

One class of small arms to which my present 15 improvements are applicable, includes the auto-loading pistols having a grip-stock, or handle-portion of the frame or receiver of the firearm, which is adapted to receive a grip-safety device operable by hand grip 20 or compression.

An improved auto-loading pistol of this kind is described in my patent No. 1,348,733, dated August 3, 1920, and granted on my copending application (renewal) Serial No. 25 311,689, filed July 17, 1919, but the improvements herein described and claimed are not illustrated or claimed in my said patent. Therefore, for convenience of illustration, I have herein shown my present improvements as arranged and applied to the particular kind of auto-loading pistol shown 30 in the drawings of said patent, to which reference may be had.

The features of my present grip safety 35 device, are that it is a grip-stock or handle contained safety device, arranged to prevent firing of the firearm by locking the firing member or hammer and the trigger-sear when my device is in normal or safety position, and where the firearm is provided with 40 a sliding breechaction, to lock the sliding breechaction.

Another feature is that while this shiftable 45 slidable member or controller serves to lock the firing member and trigger-sear, and also to lock the sliding breechaction where the firearm is provided with such breechaction, it forms an interposed means or disconnector between the trigger-sear and 50 the trigger-member, so that pull on the trigger-member will not unlock the firing member or hammer and trigger-sear, and sliding breechaction, as the case may be, except upon prior or accompanying compression of the 55 grip-safety portion of my device.

Another feature is that compression of the grip-safety member of my device, when the

same is in normal or safety position, does not release the shiftable slidable member before mentioned, but sets or pre-arranges 60 said grip-safety member for releasing said shiftable slidable member when said member is moved or shifted by contact or engagement therewith of the trigger-member due to pull on the trigger member. 65

In the accompanying drawings, which illustrate an embodiment of my invention, Figure 1, is a side elevation, partly broken away of a pistol provided with my grip-safety device, my device being in normal or 70 safety position.

Fig. 2, is a fragmentary side view, partly broken away, of the rear of a pistol provided with my grip-safety device, showing the grip safety member of my device slightly 75 compressed preparatory to firing, the shiftable slidable member or controller being at the commencement of downward movement to unlock the firing member or hammer and the trigger-sear, and to unlock the sliding 80 breechaction, where the firearm has such breechaction, the trigger-member not yet being engaged or in contact with the shiftable slidable member or controller to shift it.

Fig. 3, is a fragmentary side view, partly 85 broken away, of the rear end of a pistol provided with my grip-safety device, showing the grip-safety member of my device compressed, the shiftable slidable member or controller being in lowered or down position, and the lower end thereof shifted or swung inwardly due to pressure thereon of the trigger-member and thereby disengaged or unlocked from the grip-safety member, the firing member or hammer being in fired 90 position and unlocked from the trigger-sear, and the sliding breechaction unlocked.

Fig. 4, is a sectional view of my grip-safety device on the line 4—4 of Fig. 2, looking in the direction of the arrow. 100

My grip-safety device generally denoted by G, comprises a grip-safety member G', which is hand compressible or yieldable, and is shown pivoted at its lower end by means of a pivot pin g, to the frame or receiver B 105 of the firearm near the lower end of the grip-stock thereof. Figs. 1, 2 and 3.

The member G' closes the slot or space 2^s formed in the grip-stock of the pistol to receive the grip-safety device, and which slot or space is of use in assembling the details of my device. The upper end G² of the grip-safety member engages or contacts rearwardly with the grip-stock of the firearm 110

when the grip-safety member G' is in normal or safety position. The top portion of the grip-safety member is slotted out at 7^a , to furnish clearance for the hammer H and 5 the sear S , leaving a pair of locking prongs 7^t . These prongs or lever-arms 7^t are located outside of, and clear of, the rear end of the trigger member F , and when the grip-safety member is in its rearward or safety position, 10 the prongs 7^t are immediately below the under sides or bottom-sides 16 of the lower ends 15 of the shiftable slidable member or controller N , which is thereby locked against downward movement.

15 The grip-stock of the firearm is bored out to receive the spring 8^e , which is seated in the lower end of the grip-stock, and at its upper end abuts or engages a sliding plunger 8^e , which slides in the boring for the 20 spring 8^e in the grip-stock. The plunger 8^e is cupped at its upper end to receive the rounded end of a lower spring rod or connecting rod 8^b , which is pivotally attached at its upper end to a sliding member or 25 block 10 , which slides in a guideway 11 , formed by the grip-safety member G' and a slide face 8^2 in the grip-stock. An upper spring rod or connecting rod $8^{b'}$, is pivotally attached at its lower end to the sliding mem- 30 ber or block 10 , and is pivotally attached at its upper end to the firing member or hammer H , the effect of the spring 8^e being to throw or press the hammer H forwardly at all times. When the hammer H is in its 35 cocked position, Fig. 1, a line drawn through the center of the pivot connection of the upper spring rod $8^{b'}$ to the hammer H and through the center of the pivot which connects the upper spring rod $8^{b'}$ and lower 40 spring rod 8^b , to the sliding member or block 10 , will pass to the rear of the center of the plunger 8^e , which being seated in the grip-stock provides a fixed pivotal point. Hence the action of the spring 8^e tends to hold the 45 grip-safety member G' in its rearmost position when the hammer is in firing position or cocked.

If the hammer H is released to its fired or uncocked position, Fig. 3, after the upper 50 end of the grip-safety member, as at G^2 , is moved to its forward position, a line drawn through the pivot connection of the upper spring rod $8^{b'}$ to the hammer H and lower spring rod 8^b , to the sliding member or block 55 10 , will pass forward of the center of the plunger 8^e , so that the action of the spring 8^e will be to hold the grip-safety member G' in its forward or compressed position. The advantage of this latter arrangement is that 60 the reaction of the spring 8^e on the grip-safety member G' , due to the sudden arresting of the hammer H when it strikes the firing pin of the firearm, will be neutralized and have no tendency to sting the hand of 65 the user of the firearm. The shiftable mem-

ber or controller N is slideable upwardly and downwardly in an opening 12 , in the frame or receiver B , the opening 12 , being wider at its lower end than at its top to allow swinging or shifting of the controller. The controller N , is provided at its upper end with a point 14^d to engage the sliding breech-action of the firearm, and provided with a forwardly projecting nose 13 , to engage the forward side of the opening 12 , and thereby 75 to allow the lower end of the controller to swing or shift rearwardly and inwardly under rearward pressure on said lower end, when the controller N is in downward or unlocking position. Figs. 1 and 3, the shiftable slidable member or controller N has shoulders 14^p , provided with engaging surfaces 14^e , and extending lower ends 15 , and under sides or bottom-sides 16 of said ends. 80 15 engageable with the locking prongs 7^t of the grip-safety member G' . The lower end or bottom 17 , of the shiftable slidable member or controller N , preferably has an upwardly inclined surface 18 , or other suitable means, for engaging a spring operated actuator 19 , the purpose of which surface or means is, by engagement of the actuator 19 therewith, to force the lower end of the controller N outwardly, or in other words, to return the controller to position after shifting thereof. The actuator 19 is located in a suitable boring in the grip-stock below the lower end of the shiftable slidable member or controller N , and comprises a spring 20 , seated in said boring and abutting a projectable member or nose-piece 21 , which preferably has a rounded end 22 or other suitable means for engaging the lower end of the shiftable slidable member or controller N , the tendency of the actuator 19 , 100 being to move or thrust the shiftable slid- 105 able member or controller N , upwardly and to retain it in this position, and also to push the lower end of the shiftable slidable member or controller N outwardly as above explained. The firing member or hammer is pivotally attached to the frame of the firearm and is provided with a firing or lock-notch 8^4 , and an eccentric cam face 8^k . 110 The sear member S , is pivotally attached to the grip-stock and is provided with a locking shoulder 17^b which is engageable with the lock-notch 8^4 of the hammer H , and is provided with a face or surface 17^a which is engageable with the eccentric cam 115 face of the hammer. The sear member S , is further provided with arms S^{10} having extending ends 17^t , which are engageable with the upper surfaces 14^e of the shoulder of the controller N , and is provided with a project- 120 ing end 17^d which is engageable with the rear side of the shiftable slidable member or controller N .

For the purpose of maintaining the gear member S in such engagement or contact, 130

a contactor 23 is provided. The contactor 23, consists of a spring socketed at one end in a recess in the grip-safety member G' and socketed at the other end in a recess in the sear S, the tendency of the contactor 23, being to hold the projecting end 17^a of the sear in engagement with or to press against the rear side of the shiftable slidable member or controller N, when the grip-safety member G' is in normal or safety position, Fig. 1.

The trigger member F, is movable rearwardly by pull thereon, and is movable forwardly by means not shown, and the rear end thereof passes through an opening 2^a in the grip-stock and is engageable with the forward side of the shiftable slidable member or controller, N, which opening 2^a is of sufficient width to permit upward and downward movement or play of the trigger-member F therein.

In operation, my grip-safety device being in normal position or position of safety, Fig. 1, the end G^a of the grip-safety member is in engagement with the frame of the firearm.

The hammer H is in firing position or cocked, the locking shoulder 17^b of the sear member S is in engagement with cock-notch 8^b of the hammer, and the projecting end 17^a of the sear, through pressure of the contactor 23, is in engagement with rear side of the shiftable slidable member or controller N, but the ends 17^c of the sear are out of engagement with the upper surfaces, 14^a, of the shoulder 14^b, of the shiftable slidable member or controller, the shiftable controller N, thereby acting as a disconnector, or interposed means, between the rear end 40 of the trigger-member F and the projecting end 17^a of the sear.

The shiftable slidable member or controller N thus is in upward or locking position, and is so held by pressure of the actuator 19, and prevented from downward movement by the engagement of the locking prongs 7^c with the bottom sides or bottom ends of the lower ends 15 of the shiftable slidable member or controller. The engagement of the locking-prongs 7^c, when the grip-safety member G' is in this position, Fig. 1, is with the inward or rearward end portion of the under sides or bottom sides of the lower ends 15, the purpose of this arrangement being now explained.

Grip-compression of the grip-safety member G disengages the end G^a thereof from the frame, and moves the locking prongs 7^c forwardly or outwardly, Fig. 2, so that it is the forward or outward end portion of the bottom sides of the lower ends 15, of the shiftable slidable member or controller which are then in engagement with the locking-prongs 7^c, and the grip-safety member is thus set, or perarranged, for

releasing by shifting the lower end of the shiftable slidable member or controller inwardly or rearwardly by pull upon the trigger-member F, to release the locking-prongs 7^c and also forcing inwardly or rearwardly the projecting end 17^a of the sear S to revolve the sear, thereby unlocking the shoulder 17^b of the sear from the cock-notch 8^b of the hammer H and permitting movement of the hammer to fired position.

The shiftable slidable member or controller N, is then in downward or unlocking position, being moved to this position by the engagement of the eccentric cam face 8^c with the engaging surface or face 17^a of the sear when the hammer is actuated to fired position by the firing spring, the ends 17^c of the arm S¹⁰ of the sear in its revolution or movement engaging or bearing down upon the upper surfaces 14^a, of the shoulder 14^b of the shiftable slidable member or controller, and forcing it downward against the pressure of the actuator 19. The actuator 19, when pressure of said ends 17^c is relieved forces or moves the shiftable controller N upwardly and forwardly or outwardly, and returns the shiftable slidable member or controller N to upward or locking position. Release of grip-compression returns the grip-safety member to normal position or position of safety to block the shiftable slidable member or controller in locking position.

Having thus described my invention, I claim:

1. In a firearm, in combination, a frame of said firearm, a firing member movable to firing position and to fired position, a sear member engageable with said firing member, a shiftable slidable member, means for moving said shiftable member in direction to lock said sear member and firing member in firing position, said sear member being engageable with said shiftable slidable member to move the shiftable slidable member in direction reverse to the first mentioned direction when said firing member is moved to fired position, a grip-compressible member engageable with said frame and engageable with said shiftable slidable member when in position of safety to block the shiftable slidable member in said locking position, and by grip-compression releasable from engagement with said frame and settable for releasing the shiftable slidable member, and a trigger engageable with said shiftable slidable member to shift the same, when said grip-compressible member is grip-compressed, to release said grip-compressible member from engagement with said shiftable slidable member, and move said sear member for releasing said firing member for movement to fired position.

2. In a firearm, in combination, a frame of said firearm, a sliding breechaction, a firing

120

125

130

- member movable to firing position and to fired position, a sear member engageable with said firing member, a shiftable slidable member engageable with said sliding breech-
5 action, means for moving said shiftable slid-
able member in direction to lock said sliding breechaction and lock said sear member and firing member in firing position, said sear member being engageable with said
10 shiftable slidable member to move the shiftable slid-
able member in direction reverse to the first mentioned direction when said firing member is moved to fired position, a grip-
compressible member engageable with said
15 frame and engageable with said shiftable slid-
able member when in position of safety to block the shiftable slidable member in said locking position, and by grip-com-
pression releasable from engagement with said
20 frame and settable for releasing the shiftable slidable member, and a trigger engage-
able with said shiftable slidable member to shift the same, when said grip-compressible member is grip-compressed, to release said
25 grip-compressible member from engagement with said shiftable slidable member, and move said sear member for releasing said firing member for movement to fired position.
3. In a firearm, in combination, a frame of
30 said firearm, a firing member movable to firing position and to fired position, a sear member engageable with said firing member, a shiftable slidable member, means for mov-
ing the shiftable slidable member upwardly
35 to lock said sear member and firing member in firing position, said sear member being engageable with said shiftable slidable mem-
ber to move the shiftable slidable member downwardly when said firing member is
40 moved to fired position, a grip-compressible member engageable with said frame and en-
gageable with said shiftable slidable mem-
ber when in position of safety, to block the
45 shiftable slidable member in said locking
position, and by grip-compression releasable
from engagement with said frame and set-
table for releasing the shiftable slidable member, and a trigger engageable with said
50 shiftable slidable member to shift the same,
when said grip-compressible member is grip-
compressed, to release said grip-compressible member from engagement with said shiftable slidable member, and move said sear member for releasing said firing member for
55 movement to fired position.
4. In a firearm, in combination, a frame of said firearm, a sliding breechaction, a firing member movable to firing position and to fired position, a sear member engageable
60 with said firing member, a shiftable slidable member engageable with said sliding breech-
action, means for moving the shiftable slid-
able member upwardly to lock said sliding breechaction, and lock said sear member and
65 firing member in firing position, said sear
member being engageable with said shiftable
60 slidable member to move the shiftable slidable member downwardly when said firing member is moved to fired position, a grip-
compressible member engageable with said frame and engageable with said shiftable
65 slidable member when in position of safety, to block the shiftable slidable member in said locking position, and by grip-
compression releasable from engagement with
70 said frame and settable for releasing the shiftable slidable member, and a trigger engageable with said shiftable slidable member to shift the same, when said grip-com-
pressible member is grip-compressed, to re-
lease said grip-compressible member from
75 engagement with said shiftable slidable member, and move said sear member for re-
leasing said firing member for movement to
80 fired position.
5. In a firearm, in combination, a frame of said firearm, a firing member movable to firing position and to fired position, a sear member engageable with said firing member, a shiftable slidable member, an actuator for
85 moving said shiftable slidable member up-
wardly to lock said sear member and firing member in firing position, said sear member being engageable with said shiftable slid-
able member to move the shiftable slidable member downwardly when said firing member is moved to fired position, a grip-oper-
able member engageable with said frame and engageable with said shiftable slidable member when in position of safety, to block
90 the shiftable slidable member in said locking position and by grip-compression releasable from engagement with said frame and set-
table for releasing the shiftable slidable member, a spring, means comprising means
95 engaging said grip-operable member, for sliding connection of said spring to said firing member for actuating the firing mem-
ber, and affording grip-compression of the
100 grip-operable member, and for returning the
105 grip-operable member to engagement with
said frame after grip-compression, and a
trigger engageable with said shiftable slid-
able member to shift the same, when said
110 grip-operable member is grip-compressed, to
release said grip-operable member from
115 engagement with said shiftable slidable mem-
ber, and move said sear member for releas-
ing said firing member for movement to fired
120 position.
6. In a firearm, in combination, a frame of said firearm, a sliding breech action, a firing member movable to firing position and to fired position, a sear member engageable with said firing member, a shiftable
125 slidable member engageable with said sliding breech action, an actuator for moving said shiftable slidable member upwardly to lock said sliding breechaction, and lock said
130 sear member and firing member in firing

- position, said sear member being engageable with said shiftable slidable member to move the shiftable slidable member downwardly when said firing member is moved to fired position, a grip-operable member engageable with said frame and engageable with said shiftable slidable member when in position of safety, to block said shiftable slidable member in said locking position, and by grip-compression releasable from engagement with said frame and settable for releasing the shiftable slidable member, a spring, means comprising means engaging said grip-operable member, for sliding connection of said spring to said firing member for actuating the firing member, and affording grip-compression of the grip-operable member, and for returning the grip-operable member to engagement with said frame after grip-compression, and a trigger engageable with said shiftable slidable member to shift the same, when said grip-operable member is grip-compressed, to release said grip-operable member from engagement with said shiftable slidable member, and move said sear member for releasing said firing member for movement to fired position.
7. In a firearm, in combination, a frame of said firearm, a firing member movable to firing position and to fired position, a sear member engageable with said firing member, a shiftable slidable member, an actuator for moving said shiftable slidable member upwardly to lock said sear member and firing member in firing position, and for returning the shiftable slidable member to normal position after the same has been shifted, said sear member being engageable with said shiftable slidable member to move the same downwardly when said firing member is moved to fired position, a grip-operable member engageable with said frame and engageable with said shiftable slidable member when in position of safety, to block the shiftable slidable member in said locking position and by grip-compression releasable from engagement with said frame and settable for releasing the shiftable slidable member, a spring, means comprising sliding means engaging said grip-operable member and engaging said frame for operative connection of said spring to said firing member for actuating the firing member, and affording grip-compression of the grip-operable member and for returning the grip-operable member to engagement with said grip-stock after grip-compression, a trigger engageable with said shiftable slidable member to shift the same, when said grip-operable member is grip-compressed to release said grip-operable member from engagement with said shiftable slidable member, and move said sear member for releasing said firing member for movement to fired position, and means for maintaining said sear member in position for engagement therewith of said shiftable slidable member when the shiftable slidable member is moved by said trigger.
8. In a firearm, in combination, a frame of said firearm, a sliding breechaction, a firing member movable to firing position and to fired position, a sear member engageable with said firing member, a shiftable slidable member engageable with said sliding breechaction, an actuator for moving said shiftable slidable member upwardly to lock said sliding breechaction, and lock said sear member and firing member in firing position, and for returning the shiftable slidable member to normal position after the same has been shifted, said sear member being engageable with said shiftable slidable member to move the shiftable slidable member downwardly when said firing member is moved to fired position, a grip-operable member engageable with said frame and engageable with said shiftable slidable member when in position of safety, to block the shiftable slidable member in said locking position, and by grip-compression releasable from engagement with said frame and settable for releasing the shiftable slidable member, a spring, means comprising sliding means engaging said grip-operable member and engaging said frame for operative connection of said spring to said firing member for actuating the firing member, and affording grip-compression of the grip-operable member and for returning the grip-operable member to engagement with said grip-stock after grip-compression, a trigger engageable with said shiftable slidable member to shift the same, when said grip-operable member is grip-compressed to release said grip-operable member from engagement with said shiftable slidable member, and move said sear member for releasing said firing member for movement to fired position, and means for maintaining said sear member in position for engagement therewith of said shiftable slidable member when the shiftable slidable member is moved by said trigger.
9. In a firearm, in combination, a frame of said fire-arm comprising a grip-stock, a firing member movable to firing position and to fired position and provided with a cock-notch and an eccentric cam-face, a sear member provided with a locking shoulder engageable with said cock-notch and a face engageable with said cam-face of the firing member, and provided with an arm and provided with an extended lower end, a shiftable slidable controller movable upwardly to lock the sear member and firing member in firing position provided with a shoulder having upper surfaces and an end with bottom-sides, and provided with an inclined lower end, an actuator engaging said inclined lower end for moving the shiftable

slidable controller upwardly, and for returning the shiftable slidable controller to normal position after the same has been shifted, said shiftable slidable controller being movable downwardly by engagement of said arm of the sear member with said upper surfaces of the shoulder of said controller when said firing member is moved to fired position, a grip-safety member pivotally attached at one end thereof to said grip-stock and engageable at the other end thereof with said frame, and provided with locking prongs engageable with said bottom-sides of the shiftable slidable controller to block the same in upward locking position, and releasable from engagement with said frame and settable for releasing said locking-prongs from engagement with said bottom-sides by grip-compression, a spring seated in said grip-stock, a sliding member engaging said grip-stock and engaging said grip-safety member, a rod pivotally attached to said firing member and pivotally attached to said sliding member, a second rod pivotally attached at the upper end thereof to said sliding member, a cupped plunger providing a seat for the lower end of said second rod and an abutment for said spring, a trigger engageable with said shiftable slidable controller to shift the same, when said grip-safety member is grip-compressed, to release said grip-safety member from engagement with said shiftable slidable member, and move said sear member for releasing said firing member for movement to fired position, and a spring contactor operatively connecting said sear member and said grip-safety member for maintaining said sear member in position for engagement therewith of said shiftable slidable controller when the shiftable slidable controller is moved by said sear member.

10. In a firearm, in combination, a frame of said firearm comprising a grip-stock, a sliding breechaction, a firing member movable to firing position and to fired position and provided with a cock-notch and an eccentric cam-face, a sear member provided with a locking-shoulder engageable with said cock-notch and a face engageable with said cam-face of the firing member, and provided with an arm, and provided with an extended lower end, a shiftable slidable controller engageable with said sliding breechaction and movable upwardly to lock said sliding breechaction, and lock said sear member and firing member in firing position, and provided with a shoulder having upper surfaces and an end with bottom-sides, and provided with an inclined lower end, an actuator engaging said inclined lower end for moving the shiftable slidable controller upwardly, and for returning the shiftable slidable controller to normal position after the same has been shifted, said shiftable controller being movable downwardly by engagement of said arm of the sear member with said upper surfaces of the shoulder of said controller when said firing member is moved to fired position, a grip-safety member pivotally attached at one end thereof to said grip-stock and engageable at the other end thereof with said frame, and provided with locking prongs engageable with said bottom-sides of the shiftable slidable controller to block the same in upward locking position, and releasable from engagement with said frame and settable for releasing said locking-prongs from engagement with said bottom-sides by grip-compression, a spring seated in said grip-stock, a sliding member engaging said grip-stock and engaging said grip-safety member, a rod pivotally attached to said firing member, and pivotally attached to said sliding member, a second rod pivotally attached at the upper end thereof to said sliding member, a cupped plunger providing a seat for the lower end of said second rod, and an abutment for said spring, a trigger engageable with said shiftable slidable controller to shift the same, when said grip-safety member is grip-compressed, to release said grip-safety member from engagement with said shiftable slidable member, and move said sear member for releasing said firing member for movement to fired position, and a spring contactor operatively connecting said sear member and said grip-safety member for maintaining said sear member in position for engagement therewith of said shiftable slidable controller when the shiftable slidable controller is moved by said sear member.

11. In a firearm, in combination, a firing member movable to firing position and to fired position, sear means engageable with said firing member, shiftable slidable means movable in a direction to lock said sear means and firing member in firing position, and movable in a reverse direction to unlock position when the firing member is moved to fired position, and grip-compressible means for blocking said shiftable slidable means in said locking position, said grip-compressible means being movable by grip-compression and settable for releasing said shiftable slidable means for movement from said locking position when the shiftable slidable means is shifted.

12. In a firearm, in combination, a sliding breechaction, a firing member movable to firing position and to fired position, sear means engageable with said firing member, shiftable slidable means engageable with said sliding breechaction, and movable in a direction to lock said sliding breechaction, and lock said sear means and firing member in firing position, and movable in a reverse direction to unlock position when the firing member is moved to fired position, and

grip-compressible means for blocking said shiftable slidable means in said locking position, said grip-compressible means being movable by grip-compression and settable for releasing said shiftable slidable means for movement from said locking position when the shiftable slidable means is shifted.

13. In a firearm, in combination, a firing member movable to firing position and to fired position, sear means engageable with said firing member, trigger means, shiftable slidable means movable in a direction to lock said sear means and firing member in firing position, and movable in a reverse direction by said sear means when said firing member is moved to fired position, and grip-compressible means for blocking said shiftable slidable means in said locking position, and settable by grip-compression for releasing said shiftable slidable means for movement from said locking position when the shiftable slidable means is shifted by said trigger means.

14. In a firearm, in combination, a sliding breech-action, a firing member movable to firing position and to fired position, sear means engageable with said firing member, trigger means, shiftable slidable means movable in a direction to lock said sliding breechaction, and lock said sear means and firing member in firing position, and movable in a reverse direction by said sear means when said firing member is moved to fired position, and grip-compressible means for blocking said shiftable slidable means in said locking position, and settable by grip-compression for releasing said shiftable slidable means for movement from said locking position when the shiftable slidable means is shifted by said trigger means.

15. In a firearm, in combination, a frame of said firearm comprising a grip-stock, a grip-safety member engageable with said frame and pivotally connected to said grip-stock, a firing member, movable to firing position and to fired position, a spring seated in said grip-stock, sliding means engaging said grip-stock and engaging said grip-safety member, means pivotally attached to said firing member and pivotally attached to said sliding means, a second means pivotally attached at one end to said sliding means, and a plunger providing a seat for the other end of said second means and an abutment for said spring.

16. In a firearm, in combination, a frame of said firearm comprising a grip-stock, a grip-safety member engageable with said frame and pivotally connected to said grip-stock, a firing member movable to firing position and to fired position, a spring seated in said grip-stock, sliding means engaging said grip-stock and engaging said grip-safety member, a rod pivotally attached to said firing member and pivotally attached

to said sliding means, a second rod pivotally attached at one end to said sliding means, and a plunger providing a seat for the other end of said second rod and a sliding abutment for said spring; said sliding means and 70 said rods pivotally attached thereto being so arranged that a line from the center of pivotal attachment of the first of said rods to said firing member through the center of pivotal attachment of said first and second 75 rods to said sliding means will pass to the rear of the center of said plunger when said firing member is in firing position, and will pass forward of the center of said plunger when said firing member is in fired position. 80

17. In a firearm, in combination, a frame of said firearm comprising a grip-stock, a grip-safety member engageable at one end with said frame and pivotally attached at the other end to said grip-stock, a firing 85 hammer a firing spring seated in said grip-stock, a sliding member engaging a slide face in said grip-stock and engaging said grip-safety member, a rod pivotally attached at the upper end thereof to said firing hammer and pivotally attached at the lower end thereof to said sliding member, a second rod pivotally attached at the upper end thereof to said sliding member, and a plunger providing a seat for the lower end of said second rod and a sliding abutment for said firing spring.

18. In a firearm, in combination, a frame of said firearm comprising a grip-stock, a grip-safety member engageable at one end with said frame and pivotally attached at the other end to said grip-stock, a firing hammer movable to firing position and to fired position, a firing spring seated in said grip-stock, a sliding member engaging a 100 slide face in said grip-stock and engaging said grip-safety member, a rod pivotally attached at the upper end thereof to said firing member and pivotally attached at the lower end thereof to said sliding member, a second rod pivotally attached at the upper end thereof to said sliding member, and a plunger providing a seat for the lower end of said second rod and a sliding abutment for said firing spring; said sliding member and 105 said pivotally attached rods being so arranged that a line from the center of pivotal attachment of the first rod to said firing hammer through the center of pivotal attachment of said first and second rods to 110 said sliding member, will pass to the rear of the center of said plunger when said firing hammer is in firing position, and will pass forward of the center of said plunger when said firing hammer is in fired position. 115
